INVENTOR

Annie Willoughby

UNITED STATES PATENT OFFICE.

ANNIE WILLOUGHBY, OF PHILADELPHIA, PENNSYLVANIA.

CATAMENIAL SACK AND SUPPORTER.

SPECIFICATION forming part of Letters Patent No. 463,819, dated November 24, 1891.

Application filed July 16, 1891. Serial No. 399,689. (No model.)

To all whom it may concern:

Be it known that I, ANNIE WILLOUGHBY, a citizen of the United States, residing in the city of Philadelphia, county of Philadelphia, 5 and State of Pennsylvania, have invented a certain new and useful Improvement in Catamenial Sack and Supporter, of which the following is a specification.

My invention consists of the combination 10 of a garment-supporter and a pouch so constructed that the garment-supporter may be used either as a support for the ordinary under-garments or as a support for a pouch, or as a support for both at the same time, and which 15 shall be also so constructed that the pouch may be readily attached and detached without removing the supporter.

Reference being had to the accompanying drawing, my invention is described as follows:

20 I make the supporter of two braces or straps A A', of cloth, leather, or other suitable material, each strap passing over one of the shoulders of the body. I prefer to connect these two straps by a cross-brace O. The whole or 25 a portion of each strap may be made of elastic webbing, so as to give some play or elasticity to the strap. Near the ends of the straps or braces are buttons B B' B² B³, or any other ordinary fastening device, by means of which 30 one or more under-garments which it is desired to support may be attached. Below these buttons or fastening devices are other buttons C C' C² C³, or other ordinary fastening devices. To these buttons or fastening 35 devices C and C' in front of the body and C² and C³ at the back of the body are buttoned or detachably fastened two supporting devices for the pouch, one at the front and one at the back of the body. Each of these supporting devices for the pouch has at the end opposite to that at which it is attached to the straps a loop G, one end of which is detachably fastened by means of a button or other ordinary fastening device. This supporting 40 device for the pouch may be made of any desired form; but I prefer to make it as follows: A cross-piece D, of cloth or similar fabric, is

arranged to fasten to the braces A A', if in front, or A² A³, if at the back. This cross-piece is connected by two elastic links of rubber webbing E E' with another piece of cloth or similar fabric F, which has at the lower end a loop G, one end of which is detachably fastened by means of a button H, or other ordinary fastening device. 50

The pouch L, large enough to hold a sponge, is composed of soft rubber and has two soft rubber loops K K'. I prefer to make the loops of slightly-thicker rubber than the pouch and to make the loop at the front of 60 the body shorter than the loop at the back of the body. In adjusting the pouch each of the loops G, one in front and one at the back of the body, is passed through one of the soft-rubber loops of the pouch and fastened by 65 the button or other ordinary fastening device H.

It will be seen that by detaching the cross-pieces D the supporter can be used as an ordinary garment-supporter, and that with the 70 cross-pieces D attached the supporter can be used either solely as a support for the pouch or as a support both for pouch and under-garments. It will be seen, also, that by unfastening the loop G at the button or fastening H in front and in back the pouch can be 75 removed and replaced without removing the supporter from the body. The loop G may also, if desired, be used as a guard to the sponge by passing it through a loop attached 80 to the sponge.

I claim as my invention—

In combination, the braces A A', the buttons B B' B² B³, the buttons C C' C² C³, the cross-piece D, the links E E', the supporting 85 devices F, the loops G, the buttons H, the pouch L, and the loops K K', operating together as a garment-supporter and pouch, substantially as and for the purposes described.

ANNIE WILLOUGHBY.
